COMBINED BOTTLE, CAP AND BRUSH

Dorothy M. Gavin, Maplewood, N. J.

Application March 5, 1954, Serial No. 29,367

Term of patent 14 years

(Cl. D58—9)

Fig. 1

Fig. 2

Fig. 3

To all whom it may concern:

Be it known that I, Dorothy M. Gavin, a citizen of the United States, residing in Maplewood, New Jersey, have invented a new, original, and ornamental Design for a Combined Bottle, Cap and Brush, of which the following is a specification, reference being had to the accompanying drawing, forming a part hereof.

In the drawings:

I claim:

The ornamental design for a combined bottle, cap and brush, as shown.
